FAN

James D. Crook, Asheville, N. C.

Application August 18, 1938, Serial No. 225,621

15 Claims. (Cl. 230—256)

My invention relates to fans and specifically to a simple, inexpensive and effective means for causing a rotary fan, with its guard and motor, to oscillate or to rotate with reference to its base.

Another object of the invention is to provide an oscillatory fan with means whereby the length of the oscillations may be adjusted.

Referring to the drawings, which are made 10 a part of this application and in which similar reference characters indicate similar parts:

Figure 1 is a front elevation, illustrating the use of my invention.

Figure 2, a side elevation of the same.

Figure 3, a section through the fan base, showing the adjustable stroke-limiting means.

Figure 4, a similar view showing another position of the stroke-limiting means.

Figure 5, a vertical section showing electrical 20 connections, such as preferably used in connection with a fan mounted for rotation, e. g., about a vertical axis.

Figure 6, a side view of a modified valve or closure, and;

Figure 7, an elevation of the same.

In the drawings, reference character 10 indicates the stationary base of a fan to which is connected an upper adjustable portion 11 by means of a horizontal pivot bolt 12, in well 30 known manner. The part 11 has a shoulder 13 and an upwardly extending neck 14. The fan motor 15 is mounted on a tubular support 16 which has at its lower end a flange 17 connected to the shoulder 13 by means of a flanged collar 18 secured to the shoulder 13 by screws, there being roller bearings 19 interposed between flange 17 and co-acting members 13 and 18.

Current is supplied to the motor by means of conductors 20 and 21 leading to spring-pressed 40 stationary contacts 22—23 which engage respectively with a contact ring 24 and a contact 25. The contact ring 24 is connected to a conductor 26 and the contact 25 is connected to a conductor 27, contacts 24 and 25 being mounted 45 in an insulating block 28 which rotates or oscillates with the support 16, as the case may be, while contacts 22 and 23 are mounted in an insulating block 29 on the adjustable member 11 of the base 10.

50 The impeller for air comprises the fan shaft 31 carried by the armature or motor 15, as usual, and the fan blades 32. These parts and the skeleton or openwork guard may be of any desirable or conventional form. In the present case the guard has front and rear rings 33 and 34 sup-

ported by radially extending bars 35 connected to a boss 35' said rings being connected by cross bars 36, which may be integral with the radial bars 35. In effect these cross bars act as brackets to support valves now to be described.

5 For producing an oscillatory movement of the fan without the use of any gears or other complicated and expensive devices I provide valves or closure members 37 at opposite sides of the fan, these valves being shown as consisting of 10 arcuate strips of sheet metal or the like each provided at its upper end with hook-shaped ears 38 adapted to be hooked over a suitable support, here shown as consisting of a cross member 36 of the guard. At their lower ends these valves 15 have upwardly extending hooks 39 for engagement with the end portions 40 of an arcuate yoke member 41, here shown as a wire bent at its middle to provide a downwardly extending lug or finger 42 projecting from said yoke and having a 20 buffer sleeve of rubber or the like, shown at 43. It will be seen that the connector 41 maintains the valves 37—37 in a substantially constant spaced relation with reference to each other, such that either valve may be in contact with 25 the fan guard while the other is substantially spaced therefrom, as at the right in Figure 1, or both valves may be spaced equally from the fan guard if desired. It will be noted that cross members 36 adjacent the lower ends of the valves 30 are also provided with buffers, preferably in the form of rubber sleeves 44 to deaden the shock when struck by a valve 37 and to eliminate noise caused by such shocks.

35 For limiting the extent of oscillation I provide controlling means, here shown as consisting in a pair of fingers 45 and 46 pivotally supported on a projection 47 having a threaded neck 48 and a winged nut 49 thereon for clamping the fingers in adjusted position. In Figure 3 these fingers 40 are shown as positioned to afford an oscillation over an arc of about 90°, which is regarded as the normal oscillation. Figure 4 shows the fingers at the limit of their inward movement toward each other, where no oscillation of the fan 45 is permitted, the valves being held equi-distant from the fan at both sides thereof. It will be obvious that these fingers may be set at any point between the wide open position of Figure 3 and the fully closed position of Figure 4.

50 The form of base and electrical connections shown in Figure 5 is particularly adapted for a fan which rotates continuously in one direction around its base, since such a construction prevents twisting of the conductor and consequent 55

breakage. Such a form is, however, also well suited for use with an oscillatory fan, for similar reasons. When it is desired that the fan shall rotate continuously in one direction the yoke 41 and the control members 45 and 46 may be omitted, as well as one of the valves. In such cases a single valve such as shown in Figures 6 and 7 is attached to one side of the fan guard and this is preferably not attached pivotally as in Figure 1 but is formed with lugs 51 at opposite ends of the body 52 for hooking over a pair of cross members 36 of the fan guard.

In the use of a single valve for continuous rotation of the fan the valve will be attached to one side or the other of the guard, according to which direction of bodily rotation is preferred. If a single valve 52 is attached to the left hand side of the guard in Figure 1 in the manner described the fan will rotate continuously to the right in said figure for the reason that the air passes the inside of the valve at greater speed than on the outside of the valve and the pressure of the air on the inside of the valve is less because of such difference in air speed; also the air outside the valve is moving forwardly and inwardly thus creating a pressure more than normal on the outside of the valve. These unequal pressures on the valve cause the fan to oscillate. The nearer the valve is to the tip of the fan blades the faster will be the rotation as the faster will be the passage of the air and the greater the reduction of air pressure on the inside of the valve. If the valve is fixed to the right hand side of the guard the impeller and guard will rotate bodily (together with the fan motor) toward the left in Figure 1.

If oscillation of the fan is desired two valves are attached respectively to opposite sides of the guard as shown in Figure 1, these valves being connected pivotally to the cross members of the guard at their upper ends and being secured together at their lower ends by the yoke-like connector 41. If the impeller be now caused to rotate with the parts as shown in Figure 1 the entire upper portion of the fan will move toward the right in said figure until the rubber buffer 43 of finger 42 strikes the control member 46, when the entire yoke 41 will be held against further movement to the right with the body of the fan. As the fan with its motor, etc. continues to move to the right due to the momentum of such parts the control member 46 will finally pull the right hand valve suddenly into contact with the guard, at the same time snapping the left hand valve away from the guard, whereupon the direction of oscillation of the fan will be reversed, i. e., it will now move toward the left in said figure.

I am aware that numerous efforts have been made to substitute simpler and cheaper means for the toothed gears, etc., commonly used for causing rotary fans to oscillate and I am acquainted with patents for such devices, but such constructions as have been suggested are usually so placed as to interfere seriously with the air-stream proceeding from the fan, and so they detract from the efficiency of the fan. In the case of disks or vanes placed in front of the fan they also mar its appearance and such contrivances and various others that have been suggested are of such weight and construction as to be operable only with difficult for reversing the fan, if in fact they are operative at all to cause continued oscillation of the fan.

75. It will be obvious to those skilled in the art

that many variations may be made in the device herein described, all without departing from the spirit of the invention; therefore I do not limit myself to what is shown in the drawings and described in the specification, but only as required by the state of the known art.

Having thus fully described my invention, what I claim as new is:

1. In combination with an oscillatory fan and a skeleton guard therefor, valve members mounted on said guard at opposite sides of the same for shutting off the flow of air into the guard, connecting means between said valve members arranged to oscillate with said fan and being so constructed as to hold one or the other of said valve members against the guard and the other one away from the guard, and control means positioned for engagement by said connecting means at the end of each stroke of oscillation for reversing the relative positions of said valve members with regard to said guard, thereby causing the fan to oscillate.

2. A device as in claim 1, said valve member being each pivotally connected to a cross member of said guard.

3. A device as in claim 1, said valve members being each pivoted on a cross member of said guard, and said connecting means being pivotally connected to the lower ends of said valve members.

4. A device as in claim 1, said control means including members adjustable toward and away from each other to vary the oscillatory travel of said fan.

5. A device as in claim 1, said control means including a pair of independently movable elements adapted to vary the travel of said connecting means.

6. In a fan, a rotary impeller, a skeleton guard therefore, said impeller and said guard being mounted for movement on an axis other than that of the impeller, and a closure member mounted on the periphery of said guard at one side of the impeller to shut off the incoming air and thus to cause the fan to rotate bodily about said axis.

7. In a fan, a base, an impeller, a guard for said impeller, said impeller and guard being mounted for movement about an axis other than that of the impeller, and a valve member mounted on a peripheral portion of said guard, said valve member being shaped to cover a substantial area of said guard at one side thereof, and being so constructed and arranged as to shut off the air passing into said guard radially of said impeller and thus to cause movement of said fan about said other axis.

8. A valve for a rotary fan having a cylindrical guard about the ends of its blades, said valve comprising an arcuate strip of metal having means at one end for securing it to said fan guard so that it lies against the periphery of said guard.

9. A valve for a rotary fan having a peripheral guard, said valve comprising an arcuate strip of metal having means at each end for securing it to said fan guard so that it lies against the periphery of said guard.

10. A valve structure for a fan guard, comprising a pair of oppositely bowed strips of sheet material; and a connector secured to one end of each of said strips, said connector having a projecting lug midway between said strips.

11. In combination with a base, a rotary fan mounted for oscillation on said base, an open-

work guard for the fan, valve members on said guard at opposite sides of the fan adapted to prevent entrance of air into said guard, and control means for said valves constructed and arranged for positioning said valves alternately closer to the center of rotation of the fan, thereby causing the fan to oscillate on its base.

5 12. A device as in claim 11, said control means being adjustable to vary the extent of oscillation of the fan.

10 13. A device as in claim 11, said control means being operable to prevent oscillation of said fan.

14. In a fan, a rotary impeller having radially extending blades, a support therefor mounted 15 for oscillation about an axis other than that of the impeller, said support including portions lo-

cated laterally beyond said impeller blades, valves supported on said portions radially outward beyond the ends of the fan blades for movement toward and from the axis of said impeller, said valves being constructed and arranged 5 to shut off the air passing radially to said impeller, and control means for moving said valves thereby causing the fan to oscillate.

15. An electric fan comprising a rotary support, a motor thereon, a shaft driven by the 10 motor, a fan on said shaft, and a guard surrounding said fan, means located radially outward laterally of the guard for shutting off air from one side of said fan.
